UNITED STATES PATENT OFFICE.

STANLEY R. DE PUE, OF WASHINGTON, DISTRICT OF COLUMBIA, ASSIGNOR TO CORONA TYPEWRITER COMPANY, INC., OF GROTON, NEW YORK, A CORPORATION OF NEW YORK.

COMPACTIBLE TYPEWRITING-MACHINE.

1,356,813.

Specification of Letters Patent. Patented Oct. 26, 1920.

Application filed July 2, 1917. Serial No. 178,253.

To all whom it may concern:

Be it known that I, STANLEY R. DE PUE, a citizen of the United States of America, and a resident of the city of Washington, 5 District of Columbia, have invented certain new and useful Improvements in Compactible Typewriting-Machines, of which the following is a full and clear specification.

The object of this invention is to so construct the machine that it may be compacted for convenience in transportation and storage, as more fully hereinafter set forth.

In the drawing is represented a vertical, longitudinal, sectional view illustrating so much of a typewriting machine as is necessary to illustrate my present improvement.

Referring to the drawing annexed by numerals, 10 designates the main frame, on which are mounted in any suitable manner 10 the key-bars 11, each key-bar being provided with a depending ear 12 which is provided with a pin 13 in its lower end, which engages the radial slot 14 in arm 15 journaled on a rock shaft 16 affixed to the lower edges 15 of the side-bars of the frame. Each of the arms 15 is provided with an upstanding arm 17 which is connected by a rearwardly-extending link 18 to the heel of the type-bar 18' of the usual construction. The type-bars are pivotally mounted in the usual 20 manner in the type-bar segment 19. This manner of connecting the key-bars to the type-bars is advantageous in that it enables the type-bar segment to be brought well forward in the machine in order to provide 25 space enough between the type-bar segment and the rear wall of the frame to receive the platen carriage and connected parts when the machine is compacted, as more fully 30 hereinafter set forth.

At each side of the main frame is provided a pair of vertical guide ribs 20 which are engaged by channeled legs 21 of a top plate or frame 22 which carries the usual 35 platen carriage 23. This frame or plate 22 is thus made vertically slidable, and it is held in its adjusted positions in any suitable manner, preferably by spring-actuated 40 latches 24, one of which is mounted in each of the legs 21 and is adapted to engage notches 25 in the guide ribs 20, the engagement of the latches with the notches being preferably a frictional one, so that the movable frame may be raised or lowered by ap-

plying a little effort thereto and also in 55 order that, whether the frame be lifted or lowered, it will automatically lock at the desired height. The lower notches 25 are so located that when they are engaged by the latches, the rear portion of the movable 60 frame together with the platen carriage will lie behind the type segment while the mechanism carried by the movable frame will have been lowered to a point approximately 65 on a level with the upper ends of the guides 20, thus compacting the machine to the extent of movement of the frame upon the guides. The foregoing construction is more fully illustrated and described in my application filed herewith, serially numbered 70 178,252.

Depending centrally in the type-bar segment is a universal bar 26 which is adapted to be centrally struck by a projection 27 on each of the type-bars. Pivotally mounted on the depending hanger 28 carried by the platen carriage supporting frame 22 is an escapement lever 29 which normally bears against the universal bar 26 and controls the escapement wheel 30 in the usual manner, the shaft of this escapement wheel being supported from the frame 22 and being provided with a pinion 31 which engages the feed-rack 32 on the carriage. The usual spring, not shown, is provided for moving 85 the carriage, and any suitable ribbon-feeding and vibrating means, operable from the universal bar 26, may be mounted on the supplemental frame, so as to be vertically adjustable therewith. It will be observed 90 that all the carriage-feeding devices are mounted on the supplemental frame, so that when this frame is dropped down into the main frame for compactness, all the carriage-feeding mechanism will be lowered 95 therewith. The escapement 29 has a sliding contact with the universal bar and is therefore free to be bodily moved up and down. In this manner, it will be observed that I provide a very simple arrangement for materially reducing the vertical dimensions of 100 the machine.

It will be observed further that by pivoting the rocking members 15 on an axis below the key-levers, I am enabled to bring the 105 type-bars closer to the key-levers and thus obtain desirable compactness in a vertical direction.

- It will be understood that the case shift may be obtained either by shifting the supplemental frame up and down in addition to the shifting this frame receives in compacting and extending the machine, or the case shift may be obtained by vertically shifting the type-bar segment; I prefer the latter, as fully disclosed in my co-pending application filed herewith.
- 10 It will be observed that by continuing the pull upwardly on the supplemental frame 22, this frame together with all the parts connected thereto may be entirely separated from the base-frame; the advantage in this 15 is that it will give ready access to all the mechanisms carried by both the base-frame and the supplemental frame, to thereby greatly convenience the matter of cleaning and repairing the parts.
- 20 The nature and scope of the invention having been thus indicated and its preferred embodiment having been specifically described, what is claimed as new is:
1. In a collapsible typewriter, a base-frame carrying the printing instrumentalities, a supplemental-frame carrying the platen carriage and escapement mechanism, and means whereby this supplemental-frame together with said escapement mechanism 30 and platen carriage may be, as an entirety, slidably separated from the base frame.
  2. In a collapsible typewriter machine, the combination of a base frame, a type bar action mounted on the base frame, a universal bar mounted on the base frame and operable by the type bars, a platen carriage, a carriage support, connections between said support and the base frame whereby said support may be shifted relatively to the base 40 frame to place the carriage in a lower upright position at the rear of the type bar action to reduce the height of the machine when not in use, and carriage feeding mechanism operable by the universal bar and 45 movable as an entirety with the carriage and carriage support relatively to the universal bar to a lower position out of co-operative relation with the universal bar when the machine is collapsed.
  - 50 3. In a collapsible typewriter machine, the combination of a base frame, a type segment mounted on the base frame, type bars pivotally mounted on said segment, key levers mounted on the base frame and operatively connected to actuate the type bars, a universal bar supported on the type segment within the arc of the segment and operable by the type bars, a platen carriage, a carriage support, connections between said 55 support and the base frame whereby said support may be shifted relatively to the base frame to place the carriage in a lower upright position at the rear of the type segment to reduce the height of the machine 60 when not in use, and carriage feeding mech-

anism operable by the universal bar and movable as a unit in its entirety with the carriage and support to a lower position out of co-operative relation with the universal bar when the machine is collapsed. 70

4. In a collapsible typewriting machine, the combination of a base frame, a supplemental frame, sliding connections between said frames whereby the supplemental frame may be moved vertically up and down 75 on the base frame to collapse and extend the machine, a universal bar, a type bar action mounted on the base frame, a platen carriage mounted on the supplemental frame, and carriage-feeding mechanism operable by the universal bar and movable in its entirety with the carriage and supplemental frame to a lower position out of co-operative relation with the universal bar.

5. In a collapsible typewriting machine, 80 the combination of a base frame, a supplemental frame, sliding connections between said frames whereby the supplemental frame may be moved vertically up and down on the base frame to collapse and extend the 85 machine, a type bar action mounted on the base frame, a universal bar operable by the type bars and supported within the base frame independently of the supplemental frame, a platen carriage mounted on the 90 supplemental frame to move therewith in a vertical plane at the rear of the type bars and universal bar, and carriage-feeding mechanism located below the carriage and mounted to move in its entirety vertically 95 with the carriage and supplemental frame into and out of co-operative relation with the universal bar.

6. The combination with a base-frame carrying printing instrumentalities and an 100 upright universal bar, of a supplemental-frame rectilinearly slidable to a point behind said universal bar for compactness, said supplemental-frame carrying a platen carriage and a complete escapement mechanism, the construction being such that when 105 the supplemental-frame is slid up to operative position the operating elements of the escapement mechanism will be moved into position to be operated by the universal bar. 110

7. In a collapsible typewriter, a base-frame carrying the type-bars and the operating mechanism thereof, and a supplemental frame carrying the platen carriage and the carriage-feed mechanism, said supplemental frame being vertically slidable upon the base-frame and readily detachable therefrom as an entirety and by a vertical sliding action. 115

8. The combination of a base-frame carrying printing instrumentalities, including an upright segment carrying a depending universal bar, a supplemental-frame carrying the complete escapement mechanism and the platen carriage, means whereby this supplemental frame 120

mental-frame is slidable rectilinearly down behind the universal bar to obtain compactness.

9. The combination with a base-frame carrying printing instrumentalities, including a segment and a universal bar, of a supplemental-frame slidable rectilinearly down behind the segment for compactness, said supplemental-frame carrying a platen car-

riage and a complete escapement mechanism, the latter depending from the supplemental-frame to bring its operating elements into operative relation with the universal bar when the supplemental-frame is in its extended or operative position. 10

This specification signed this second day of July, A. D. 1917. 15
